UNITED STATES PATENT OFFICE.

JOHN PRIMROSE, OF RICHMOND, NEW YORK, ASSIGNOR TO POWER SPECIALTY COMPANY, OF NEW YORK, N. Y., A CORPORATION OF NEW YORK.

HEAT EXCHANGER.

Application filed March 23, 1923. Serial No. 627,169.

My present invention consists in improvements in heat exchangers of the type comprising a plurality of tubular elements arranged side by side and each comprising an inner tube and an outer tube which is larger in internal diameter than the external diameter of the inner tube, and connections whereby one fluid may be passed in series through different inner tubes of the elements, and another fluid receiving heat from or imparting it to the first fluid, may be passed in series through the annular spaces between the inner and outer tubes of various tubular elements.

15 The general object of my invention is to provide improved end connections for the tubular elements of a heat exchanger of the type specified, and my invention is characterized by the simplicity and effectiveness of 20 the end connections, and a relative ease with which they permit the apparatus in which they are used to be assembled and taken apart when necessary for cleaning or repairs and by the fact that the tubular elements 25 of a single heat exchanger are arranged in groups, any one of which may be readily cut out of service for cleaning, inspection or repairs, or to reduce the flow capacity of the heat exchanger as a whole.

30 The various features of novelty which characterize my invention are pointed out with particularity in the claims annexed to and forming a part of this specification. For a better understanding of the invention, 35 however, its advantages and specific objects attained by its use, reference should be had to the accompanying drawings and descriptive matter in which I have illustrated and described a preferred embodiment of my invention.

40 Of the drawings:

Fig. 1 is an elevation of a heat exchanger, in section on the line 1—1 of Fig. 2;

45 Fig. 2 is an elevation partly in section on the line 2—2 of Fig. 1;

Fig. 3 is a section taken similarly to Fig. 1, but on a larger scale, and illustrating the tube connections employed at one end of the heat exchanger;

50 Fig. 4 is a view similar to Fig. 3 illustrating

the tube connections at the opposite end of the heat exchanger;

Fig. 5 is a partial section on the line 5—5 of Fig. 4; and

Fig. 6 is a partial section on the line 6—6 of Fig. 5.

The heat exchanger shown in the drawings comprises a plurality of tubular elements, each consisting of an outer tube A, surrounding an inner tube a, the external 60 diameter of which is less than the internal diameter of the outer tube. The tubular elements are arranged in rows or sections, each comprising a plurality of elements connected in pairs at opposite ends of the ex- 65 changer, and forming a separate, and separately usable section or unit, as hereinafter explained. The tubular element at each end of each row or section, is connected to a corresponding chambered member B. The 70 latter is formed with an opening B' in its wall in which the end of the outer tube of the corresponding element is secured with the bore of said tube in open communication with the chamber B² of the member 75 B. The corresponding inner tube a of the element, extends through the chamber B², and through an opening in the wall of the member B which is normally closed by a tubular part B³ in which the end of the tube 80 a is secured. The space B² is thus in communication with the annular space between the corresponding tube a and the tube A surrounding it. The chamber space B² in the member B at one end of each row of 85 elements is connected by a valve EA to a header FA, and the interior of the corresponding tube a is connected by the tubular part B³ and a valve C to a header D. The space B² in the member B at the opposite 90 end of the section is connected by a valve E to a header F, and its tubular part B³ is connected by a valve CA to a header DA.

At the opposite end of the exchanger from that at which the headers B are located, the 95 outer tubes A of the different elements are connected in pairs by headers G. Each header G is in the form of a box having a removable head G' at its outer end, and having apertures G² at its inner end in which 100

the outer tubes of the connected elements are secured. The two inner tubes *a* of the two elements having their outer tubes *A* connected by a header *G* are connected by a device in the form of a return bend member *H* located within the corresponding header *G*. In the open ends of the header *H* the ends of the tubes *a* are suitably secured as by welding, or by a threaded connection, the threaded connection being preferably employed when the part *H* is made of cast iron, and the welded connection being employed when the part *H* is made of steel. The return bends *H* and headers *G* are shaped to provide a flow space or channel connecting the annular spaces between the inner and outer tubes of the two tubular elements connected by each return bend *H* and the enclosing header *G*.

To properly position the inner tubes *a* in their enclosing tubes, and at the same time permit of freedom for the thermal elongation and contraction of the inner tubes relative to the outer tubes, each return bend *H* is advantageously formed with a bearing rim *H'* which loosely fits between bearing surfaces *G'* provided for the purpose at the outer end of the chamber in the corresponding member *G*. As shown, these bearing surfaces comprise extensions *G''* formed by the inner surfaces of finger-like portions of the member *G*, which extend into the enlarged portion of the chamber in the member *G*, and also serve to provide strengthening metal adjacent the holes formed in the member *G* for the bolts securing the header *G'* in place.

At the opposite end of the heat exchanger from that at which the headers *G* are located, the intermediate tubular elements are connected in pairs by means of inner box-like headers *HA* and outer headers *GA*. Each header *HA* is formed with openings *H²* in which the adjacent ends of the corresponding tubes *a* are secured, and with registering hand hole openings *H³*. The closing devices for the openings *H³* may well be in the form of tapered threaded pipe plugs *I*. The headers *GA* may be identical in construction with the headers *G* first described, and the box-like headers *HA* are shaped to engage the bearing surfaces *G'* and *G''* of their enclosing headers *GA*.

To avoid radiation losses, the outer tubular elements of the heat exchanger are enclosed in insulating material *J*, an additional insulation *K* is provided to encase the bank of tubes as a whole. Additional insulation may be provided at the ends of the heat exchanger, if desired, to cover the otherwise exposed portions of the tubular elements and the connections thereto. The tubular elements are supported by apertured tube sheets *S* and *S'*, and a structural metal framework.

The heat exchanger in the particular form shown, was primarily designed for use in

transferring heat from a relatively hot liquid supplied through the header *D* and passing in series through the tubes *a* into the header *DA*, to a relatively cool liquid supplied through the header *F* and passing through the intertube spaces of the connected elements to the headers *FA*. It will be apparent, however, that either fluid may be a liquid or a gas, and that it is not highly important whether the fluid in the tubes *a*, or the fluid in the intertube space is the hotter.

The construction described is obviously simple, effective and durable from a mechanical standpoint, and the apparatus as a whole is adapted to accommodate the relative expansion and contraction of the parts resulting from relative changes in temperature. An important characteristic of the invention is the ease with which the apparatus may be initially assembled, and may be disassembled, in whole or in part, and reassembled when necessary for cleaning or repairs, or for other purposes.

In assembling the apparatus the outer tubes *A* of the various tubular elements are first secured in the corresponding headers *G* and *GA*, and chambered members *B*, and it will be apparent that it is readily possible to secure each end of each of the outer tubes in the corresponding member *B*, *G* or *GA*, by rolling or expanding it in place as boiler tubes are ordinarily secured in boiler tube sheets. This is ordinarily the most satisfactory method of securing such parts together, and is the method employed in the heat exchanger shown. The tubes *a* are connected to the return bends or headers *H* before being inserted in the outer tubes of the tubular elements of which they are to form a part. After the tubes *a* are secured to the return bends *H*, they are put in place in the apparatus, and the opposite ends of the tubes *a* are then secured, preferably by expanding or rolling them, in the headers *HA* and members *B*. If and when it becomes necessary to remove any tube *a*, this can be effected by first detaching that tube, and the tube *a* connected to it by the corresponding header *H*, from the chambered member *B* and header *HA* or the headers *HA* at the opposite end of the apparatus to which those tubes are connected. The tubes *a* may be thus detached by cutting them away, or in other ways in which boiler and analogous tubes are separated from tube sheets and the like. After the pair of tubes *a* are thus detached, they and their connecting header can be drawn bodily out of the enclosing outer tubes and header *G*, the cover *G²* of the latter being first removed. By closing the corresponding valves *C*, *CA*, *E* and *EA*, any section of the exchanger may be cut out of service for cleaning, inspection, or repairs, or to reduce the capacity of the exchanger without interfering with the opera-

tion of the portion of the exchanger left in service.

It is possible, of course, to use headers like the headers HA in place of the single 5 return bends H. The latter offer the advantages, however, that the frictional resistance to flow through such return bends is generally appreciably less, than the resistance to flow through a header like the headers 10 HA, and the return bend is less expensive to manufacture as it is not provided with hand hole openings and the closing devices therefor.

While in accordance with the provisions 15 of the statutes, I have illustrated and described the best forms of my invention now known to me, it will be apparent to those skilled in the art that some changes in form may be made without departing from the 20 spirit of my invention as set forth in the appended claims, and that some features of my invention may sometimes be used to advantage without a corresponding use of other features.

Having now described my invention, 25 what I claim as new and desire to secure by Letters Patent, is:

1. In a heat exchanger comprising a plurality of side by side tubular elements each 30 comprising an inner tube and an outer tube the internal diameter of which is greater than the external diameter of the inner tube, headers connecting each outer tube at one 35 end to the adjacent end of another outer tube and at its other end to the adjacent end of a third tube, and connecting devices located one within each of the first mentioned headers and connecting the two corresponding inner tubes, said headers having 40 heads each removable to permit access to, and the removal of the corresponding connecting device.

2. In a heat exchanger comprising a plurality of tubular elements each comprising 45 an inner tube and an outer tube the internal diameter of which is greater than the external diameter of the inner tube, headers connecting adjacent ends of the outer tubes together in pairs, and connecting devices 50 located one within each of the first mentioned headers and connecting the corresponding inner tubes, each header and the device enclosed by it being relatively shaped to provide a flow path between the inter-tube 55 spaces of the two tube elements and to permit relative axial movement of the inner and outer tubes of the connected members while holding the inner tubes centrally with respect to the outer tubes.

60 3. In a heat exchanger comprising a plurality of tubular elements arranged side by side and each comprising an inner tube and an outer tube the internal diameter of which is greater than the external diameter of the 65 inner tube, headers connecting adjacent ends

of the outer tubes together in pairs, each of said headers being formed with a removable head, and connecting devices located one within each of the first mentioned headers and connecting the corresponding inner 70 tubes, the said connecting devices at one end of the heat exchanger having tube openings for the various tubes connected thereto and other openings through which the various tubes connected thereto may be expanded 75 into the corresponding tube openings, and removable means for closing the last mentioned openings.

4. In a heat exchanger comprising a plurality of tubular elements arranged side by 80 side and each comprising an inner tube and an outer tube the internal diameter of which is greater than the external diameter of the inner tube, headers connecting adjacent ends of the outer tubes together in pairs, and into 85 each of which the ends of the outer tubes connected by it are expanded, each of said headers being formed with a removable head, and connecting devices located one within each of the first mentioned headers and connecting the corresponding inner tubes, said devices at one end of the apparatus being 90 each formed with hand hole openings and having the ends of the inner tubes which it connects secured thereto by expanding them 95 into place.

5. In a heat exchanger comprising a plurality of tubular elements each comprising an inner tube and an outer tube the internal 100 diameter of which is greater than the external diameter of the inner tube, headers connecting adjacent ends of the outer tubes together in pairs, and connecting devices located one within each of the first mentioned headers and connecting the corresponding 105 inner tubes, each header and the device enclosed by it being relatively shaped to provide a flow path between the inter-tube spaces of the two tube elements and to provide coacting bearing surfaces at the outer 110 end of said device and on the adjacent portion of the header permitting relative axial movement of the inner and outer tubes of the connected members while holding the inner tubes centrally with respect to the 115 outer tubes.

6. A heat exchanger comprising a plurality of tubular elements arranged side by side and each comprising an inner tube and an outer tube the internal diameter of which 120 is greater than the external diameter of the inner tube, means connecting the intertube spaces of the elements for series flow therethrough, comprising headers having tube openings into which the ends of the outer 125 tubes are expanded and each having a removable head and serving to connect two outer tubes, connecting devices at one end of the exchanger each connecting one end of each inner tube to the corresponding end 130

of another inner tube and each located in a corresponding header and with its attached tubes insertable in and removable from said header when the removable head of the latter is removed and connecting devices for the inner tubes at the opposite end of the exchanger, each located in a corresponding connecting header and formed with two tube holes and normally closed hand hole openings and each having the ends of two inner tubes expanded in its tube holes.

Signed at New York in the county of New York and State of New York this 20th day of March A. D. 1923.

JOHN PRIMROSE.
